UNITED STATES PATENT OFFICE.

MIECZYSLAW ROBASZEWSKI, OF SOUTH BEND, INDIANA.

REMOVABLE HEEL-PLATE.

1,163,261.

Specification of Letters Patent.

Patented Dec. 7, 1915.

Application filed August 30, 1915. Serial No. 48,028.

To all whom it may concern:

Be it known that I, MIECZYSLAW ROBASZEWSKI, a subject of the Emperor of Germany, residing at South Bend, in the county 5 of St. Joseph and State of Indiana, have invented certain new and useful Improvements in Removable Heel-Plates, of which the following is a specification.

This invention relates to certain new and 10 useful improvements in removable heel plate.

The primary object of the invention is the provision of a removable layer or plate readily secured in position upon the tread portion of a shoe heel, the same being formed 15 of metal or any desirable material.

A further object of the device is the provision of a heel plate adapted to be detachably secured to a shoe heel for completely covering the tread portion thereof, the plate- 20 receiving surface of the heel being unprovided with projections or obstructions.

A still further object of the invention is the provision of a readily removable heel plate preferably formed of metal and se- 25 curely attached when operatively positioned, the same being adjustable by reason of the flexibility of the plate.

With these general objects in view and others that will appear as the nature of the 30 invention is better understood, the same consists in the novel combination and arrangement of parts hereinafter more fully described, illustrated in the accompanying drawings, and pointed out in the appended 35 claims.

In the drawings forming a part of this application and in which like-designating characters refer to corresponding parts throughout the several views: Figure 1 is 40 a bottom plan view of the heel portion of a shoe with the plate removed. Fig. 2 is a top plan view of the plate removed. Fig. 3 is a side elevation of a heel portion of a shoe provided with the present device, parts be- 45 ing broken away. Fig. 4 is a transverse sectional view through the elements as illustrated in Fig. 3, and Fig. 5 is a perspective view of the heel plate removed.

Referring more in detail to the drawings, 50 a shoe 10 is herein illustrated provided with a heel 1 substantially of the usual form and having the lower surface 12 thereof pro- vided with oppositely arranged sockets 13, metallic plates 14 being countersunk in the 55 heel 11 overlying the said sockets 13 and pro- vided with arcuate-shaped slightly tapered

slots 15 communicating with the said sockets 13. A heel plate 16 is provided of any desirable slightly flexible material and preferably metal, the same being of any desired thickness, but having the peripheral configuration of the exterior of the shoe heel. Headed attaching lugs 17 are provided upon one face of the plate 16, the same projecting a predetermined required distance therefrom. The said slots 15 have their correspondingly opposite ends 18 enlarged and forming substantially circular openings adapted for the reception of the heads of the plate lugs 17. It will thus be apparent that the plate 16 may be positioned upon the lower shoe heel surface 12 with the lugs 17 inserted through the slot ends 18 into the sockets 13 and then the plate shifted upon the heel surface 12 until the edges of the 75 plate and heel coincide. In a reverse manner, the plate may be removed from the heel. The plate 16 is provided upon one edge thereof with a marginal short flange 19. It will be seen that when the plate 16 is thus attached to the heel and swung to its operative position with its edges lying flush with the sides of the heel 11, the lugs 17 will be firmly seated wedged within the slightly tapered slots 15 and in contact with the reduced ends 19' of the said slots, whereby to prevent accidental displacement of the same, while the flange 19 will then be seated flatly against the outer surface of the heel as best illustrated in Figs. 3 and 4 of the drawings. 90

It will be noted that during the shifting of the plate, both while applying and removing the plate, the flange 19 engages the shoe face 12, so that it is necessary to bend the plate 16 for the purpose of inserting the lugs 17 within the slots 15 and when the flange 19 reaches the edge of the heel, the same slips thereover into its locking position, while the flexibility of the plate closely contacts the same against the bottom of the heel. 100

While the form of the invention herein shown and described is what is believed to be the preferred embodiment thereof, it is nevertheless to be understood that minor changes may be made without departing from the spirit and scope of the invention as claimed. 105

What I claim as new is:-

1. In combination with a shoe heel having 110 spaced recesses upon the lower surface thereof, countersunk plates secured overlying the

said recesses and having slightly tapered arcuate slots therethrough in communication with the said sockets, the relatively opposite ends of the said slots being enlarged substantially circular in form, a flexible tread plate, and plate engaging securing means carried by the said tread plate and constructed and arranged to be moved into wedging engagement with the tapered ends of the slots.

- 10 2. In combination with a shoe heel having spaced recesses upon the lower surface thereof, countersunk plates secured overlying the said recesses and having slightly tapered arcuate slots therethrough in communication 15 with the said sockets, the relatively opposite ends of the said slots being enlarged substantially circular in form, a flexible tread plate, headed lugs carried by the said tread plate adapted for removable reception within 20 the said slots, the shanks of said lugs constructed and arranged to be moved into engagement with the tapered ends of the

slots, and a right-angularly disposed limiting flange carried by the edge of the said tread plate.

25 3. A device of the class described comprising a shoe heel having spaced sockets therein, a cover plate for each of said sockets, the said cover plates being provided with tapered arcuate slots terminating at relatively 30 opposite ends in enlarged substantially circular openings, a flexible tread plate of the same contour as the said heel, headed lugs carried by the said tread plate removably positioned within the said slots, the shanks 35 of said lugs being constructed and arranged to be moved into wedging engagement with the tapered ends of the slots, and a limiting side flange carried by the said tread plate and positioned in contact with the adjacent 40 side of the heel when the said tread plate is operatively positioned.

In testimony whereof I affix my signature.
MIECZYSLAW ROBASZEWSKI.
